SUPERREGENERATIVE RECEIVER SYSTEM

Murray G. Crosby, Riverhead, N. Y., assignor to
Radio Corporation of America, a corporation
of Delaware

Application March 6, 1943, Serial No. 478,254

13 Claims. (Cl. 250—20)

My present invention generally relates to super-regenerative receiving systems, and more particularly to a super-regenerative receiver of angle modulated carrier wave energy.

In the past there have been proposed various circuit arrangements for receiving angle modulated carrier wave energy with a receiving system employing super-regeneration. By the term "angle modulated carrier wave energy" is meant generically either frequency modulated (FM) carrier wave energy, phase modulated (PM) carrier wave energy, or hybrids thereof. The prior circuit arrangements have generally utilized a pair of super-regenerative detector tubes whose respective input electrodes were presented with sloping filter characteristics of complementary nature. A super-audible quench oscillator applied the super-audible quench oscillations to the detector tubes in alternate sequence. Various disadvantages exist in such prior arrangements. For example, the possibility of oscillation between the quench oscillator and the detector output circuits exists. Again, the super-regenerative detector tubes may be inadvertently coupled together thereby preventing proper discrimination of the angle modulated carrier wave energy applied to the detector tubes.

It may, therefore, be stated that it is one of the main objects of my present invention to provide a super-regenerative receiving system of angle modulated carrier wave energy which is free from the aforementioned disadvantages, and which offers all the advantages which exist when utilizing super-regeneration in a receiving system.

Another important object of my invention is to provide a super-regenerative receiving system for modulated high frequency carrier energy, wherein the received modulated carrier energy is applied to a pair of super-regenerative oscillator circuits subjected to alternate quenching at a super-audible frequency, and the output of the super-regenerative oscillators being subjected to detection as a separate step.

Another important object of this invention is to provide a pair of super-regenerative oscillator circuits which have input circuits oppositely off tune with respect to the mean frequency of applied FM signal energy, there being employed amplifier coupling tubes between the point of origin of the FM signal energy and the off-tuned input circuits of the oscillators whereby the aforementioned mistuned input circuits are isolated from each other.

Still another object of my invention is to provide a super-regenerative receiving system wherein detection is accomplished in a stage distinct from that of super-regenerative amplification.

Yet another object of the invention is to provide a super-regenerative receiving system where-

in modulated high frequency energy to be detected is first applied to a super-regenerative amplification stage, and subsequent to such amplification is applied to an infinite impedance detector to produce the modulation signals.

The novel features which I believe to be characteristic of my invention are set forth with particularity in the appended claims; the invention itself, however, as to both its organization and method of operation will best be understood by reference to the following description, taken in connection with the drawing, in which I have indicated diagrammatically a circuit organization whereby my invention may be carried into effect.

In the drawing:

Fig. 1 shows a circuit diagram of a receiver embodying the invention.

Fig. 2 graphically illustrates the resonance curves of the input circuits of the super-regenerative oscillators.

Referring to Fig. 1 of the drawing, the numeral 1 designates a signal input transformer whose coupled primary and secondary circuits 2 and 3 are each tuned to the carrier frequency of applied modulated high frequency signals. These applied signals may be FM signal energy, or AM signal energy. Indeed, as stated heretofore, they may be PM signals. The receiving system may be of the superheterodyne type. That is to say, the signal energy fed to transformer 1 from prior circuits could be subjected to prior superheterodyning so that the signal energy applied to the primary circuit 2 could be of an intermediate frequency (I. F.). Further, the signal energy applied to transformer 1 could be either in the kilocycle (kc.) range, or in the megacycle (mc.) range. For the purposes of the present application, let it be assumed that the signal energy applied to transformer 1 has been reduced to an I. F. value, and that, therefore, each of circuits 2 and 3 is fixedly tuned to the operating I. F. value.

To demodulate the applied signal energy there is provided a pair of detector tubes 4 and 5. These detector tubes are connected in infinite impedance detector circuits. This type of detector circuit is very well known to those skilled in the art, and the theory of operation thereof need not be described in detail. It is sufficient for the purposes of this application to point out that the cathode of each of the detector tubes 4 and 5 is connected to ground through a cathode resistor which is by-passed for radio frequency currents, but not for the modulation frequency currents.

Accordingly, the cathode of tube 4 is connected to ground through resistor 6, and the latter is bypassed by condenser 7 which bypasses solely the radio frequency currents. Hence, there is developed audio frequency voltage across resistor 6 which is applied in degenerative phase to the control grid 8 by virtue of the grounded grid re-

turn resistor 9. The plate 10 of tube 4 is connected to a point of positive potential of a direct current source (not shown). The tube 5 functions in the same manner as tube 4, and, hence, the corresponding circuit elements are indicated by a prime indication. It is sufficient to point out that by virtue of the audio degeneration across each of resistors 6 and 6', each of these tubes functions in the manner of a diode whose space current flow is regulated by a control grid. Another name for this type of infinite impedance detector is "degenerative plate circuit detector." This type of detector is used in order to minimize the loading of the super-regenerative amplifiers which feed the respective detectors.

The signal energy is applied to the control grids 8 and 8' by means of respective coupling condensers 11 and 11'. Each coupling condenser is connected to its respective superregenerative oscillator circuit. The functioning of each oscillator circuit is to provide the advantage of superregenerative amplification without encountering the disadvantages which arise when super-regenerative detectors are used. Considering, first, the super-regenerative oscillator circuit to which coupling condenser 11 is connected, it comprises an electron discharge tube 12. The tube 12 is shown by way of illustration as consisting of a triode, but the invention is not restricted to this type of tube. The plate 13 is connected to the high potential side of the resonant input circuit. The latter consists of coil 14 shunted by a resonating condenser 15. The cathode 16 of tube 12 is connected to ground, a predetermined intermediate point 17 on coil 14 being returned to the grounded cathode by means of the radio frequency coupling condenser 18. The control grid 19 is regeneratively coupled to the lower end of coil 14 by means of the direct current blocking condenser 20, the resistor 21 being connected from grid 19 to ground as a grid return resistor.

It will be recognized that tube 12 and its associated circuits provide an oscillator of the Hartley type. The input circuit 14-15 is tuned to a frequency F_1 , which is on one side of the mean frequency F_c of the applied FM signal energy. The coupling condenser 11 is connected to the high potential side of the input circuit 14-15. Hence, it will be seen that the super-regenerated signal energy developed across circuit 14-15 is applied through condenser 11 to the grid 8 of the infinite impedance detector tube 4.

Since the second super-regenerative oscillator circuit is an exact duplicate of the first, the corresponding circuit components are indicated by prime indications. The input circuit 14'-15' of oscillator tube 12' is tuned to a frequency F_2 , which is on the opposite side of the mean frequency F_c . The relation between the resonance curves of circuits 14-15 and 14'-15' is shown in Fig. 2. It will be seen that the peak frequencies of these input circuits are located at frequencies F_1 and F_2 . The cross-over frequency of the two resonant curves is located at F_c . The tuning condensers 15 and 15' are, of course, adjusted so that the cross-over frequency F_c shall be equal to the mean frequency of applied FM signal energy. Where desired, the frequency spacing between peak frequencies F_1 and F_2 will exceed the maximum frequency deviation of the FM signal energy.

The grid 8' of infinite impedance detector 5 is connected to the high potential side of input circuit 14'-15' by the coupling condenser 11'. In order to isolate the input circuits of the oscil-

lators, the signal input transformer 1 is coupled to the two input circuits 14-15 and 14'-15' through a pair of amplifier coupling tubes. The advantage of using separate coupling tubes to feed the two off-tuned circuits is that the off-tuned circuits are isolated. This means that they are not coupled together, and can be separately detuned as shown in Fig. 2. The coupling amplifiers may be of any well known type. Merely by way of example, they have been shown as pentode tubes 21 and 22. The signal input grids 23 and 24 of tubes 21 and 22 respectively are connected in parallel to the high potential side of the secondary circuit 3.

15 The cathodes of tubes 21 and 22 are connected to ground through their respective grid biasing networks. The plates of the coupling tubes are connected to the +B terminal of the direct current source through respective radio frequency choke coils 21' and 22'. The direct current blocking condenser 25 couples the plate end of choke coil 21' to the high potential side of input circuit 14-15. The direct current blocking condenser 25' couples the plate end of choke coil 22' to the high potential side of input circuit 14'-15'. It will now be seen that each coupling tube amplifies the signal energy applied to the signal grid thereof. Tube 21 will transfer its amplified signal energy to the input circuit 14-15 of oscillator tube 12. In the same way the coupling tube 22 will transfer amplified signal energy to its associated input circuit 14'-15' of oscillator 12'. Hence, there will be substantially no coupling between the input circuits, and their oppositely-mistuned relation will be maintained in the manner desired.

The super-regenerative functioning of the oscillators 12 and 12' is secured by virtue of the quench oscillator circuit which comprises tubes 30 and 30'. The cathodes of the two tubes are connected in common to ground. The control grid 31 is connected to control grid 31' of the opposite tube through a pair of series-related grid return resistors 32 and 32'. The junction of the grid return resistors is connected to ground. The plate 33 of tube 30 is cross-connected to grid 31' by means of the coupling condenser 34. The plate 33' of tube 30' is cross-connected to grid 31 by coupling condenser 34'. The plates 33 and 33' are connected together by the inductance coil 35 of the oscillator circuit. The midpoint of the latter is connected to the +B terminal of the direct current source through a radio frequency choke coil 36. The lower end of coil 35 is connected by lead 40 to the tapping point 17' on oscillator coil 14'. The lead 41 connects the upper end of oscillator coil 35 to the tapping point 17 on the oscillator coil 14.

It will now be seen that the quench oscillations are injected into the tank circuits of the tubes 12 and 12'. It will also be appreciated that the quench oscillatory energy is applied into the plate circuits of the pair of super-regenerative oscillators. Plate injection is employed in order to prevent spurious oscillations such as arise with grid injection. The quench oscillations are preferably at a superaudible frequency. It is not believed necessary to describe in detail the manner in which the application of the quench oscillations to the oscillator tubes 12 and 12' results in super-regenerative amplification. It is sufficient for the purposes of this application to point out that high sensitivity and gain are secured at the oscillator tubes 12 and 12' as a result of the alternate application of the quench oscillatory en-

ergy to the oscillator tubes 12 and 12'. Even if very weak signals are applied to the input circuits of these oscillator tubes, yet there will be secured a high degree of amplification by virtue of the super-regenerative action due to the alternate superaudible quenching of the oscillator tubes 12 and 12'.

However, demodulation at the oscillator tubes 12, 12' is not utilized. Instead, the function of detection takes place at the infinite impedance detector tubes 4 and 5. By separating the functions of amplification and detection there is prevented the possibility of oscillation between the quench oscillator tank circuit and the detector plate circuits. The radio frequency super-regenerative oscillations are fed to the infinite impedance detectors through capacity-resistance coupling, and, hence, the quench frequency currents will not pass to the detector tubes 4 and 5. There is then secured the dual advantage of elimination of the quench frequency current, and omission of transformer coupling between the super-regenerative oscillators and the detector circuits. It is pointed out that the tank circuit of the quench oscillator comprises coil 35 in association with the bypass condensers 18 and 18'. Furthermore, the networks 11-9 and 11'-9' are so designed as to pass the oscillatory output of tubes 12 and 12', but not the currents of quench frequency. In place of the specific detectors shown, there may be used diode rectifiers.

The audio voltage developed across each of cathode load resistors 6 and 6' is applied to a respective audio amplifier by resistance-capacity coupling. Thus, the grid 52 of audio amplifier tube 50 is coupled by direct current blocking condenser 51 to the cathode end of resistor 6. The grid 52 is returned to ground by resistor 53. Bias is supplied the grid 52 by cathode biasing resistor 54. The audio tube 50 is constructed in the same manner as amplifier tube 50'; the circuit elements pertaining thereto are designated by corresponding numerals with prime designations. The plate circuits of tubes 50 and 50' may be connected in push-pull or in push-push. Switch S connects the primary windings 60 and 61 of output transformer T in push-push relation when adjusted to contacts A. The push-pull relation is secured by adjusting the switch to contacts B. Any desired audio utilizing network may be connected to the secondary of the output transformer.

When receiving FM signals the outputs of the amplifiers 50 and 50' should be combined in push-pull relation, since the super-regenerative oscillators 12 and 12' present oppositely sloping filters to the detectors, as shown in Fig. 2. The alternate quenching of the oscillators causes the oscillatory output thereof to be delivered to the respective detectors in the form of highly amplified signal-modulated oscillatory energy. The modulation of the energy is AM at each detector input electrode, because of the action of each off-tune discriminator circuit 14-15 and 14'-15'. The discriminatory action is too well known to require further description.

When receiving AM carrier energy, switch S is thrown into "A" or push-button position. The plate circuits of tubes 50 and 50' are now in aiding, or push-push, relation. The mistuning of circuits 14-15 and 14'-15' will not affect the amplification by tubes 12 and 12'. The AM signals will have a carrier frequency of F_c , the mean frequency of F_1 and F_2 . Therefore, the average output of the amplifiers 12 and 12' will be at F_c .

Fig. 2 shows that the off-tuning of circuit 14-15 will be compensated for by the opposite off-tuning of circuit 14'-15'. This will, also, be true of the detected outputs of the infinite impedance detectors 50 and 50'. The amplified audio signal voltage will be added in push-push relation at transformer T. If desired, input circuits 14-15 and 14'-15' may be each tuned to F_c when receiving AM waves.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In a signalling system, at least one oscillator tube circuit, means for applying modulated radio signals thereto, means for quenching the oscillator at a superaudible frequency to provide super-regenerative amplification, a detector of the infinite impedance type coupled to the oscillator for deriving the modulation signals and purely capacity-resistance means coupling said detector to said oscillator thereby to prevent quench currents from passing to the detector.

2. In a signalling system, at least one oscillator tube circuit, means for applying modulated radio signals thereto, means for quenching the oscillator at a superaudible frequency to provide super-regenerative amplification, a detector coupled to the oscillator for deriving the modulation signals and purely capacity-resistance means coupling said detector to said oscillator thereby to prevent quench currents from passing to the detector, said oscillator circuit comprising a tube having a tank circuit connected in the plate circuit thereof, and said quenching means being connected to said tank circuit.

3. In a frequency modulation receiving system, a pair of regenerative amplifier circuits, each amplifier having a respective signal input tuned circuit, said signal input tuned circuits being oppositely mistuned with respect to a predetermined frequency, means for applying frequency modulated carrier energy to said respective input circuits, the center frequency of the applied energy being equal to said predetermined frequency, a quench oscillator for alternately quenching said amplifiers thereby to render them operative as super-regenerative amplifiers, a pair of infinite impedance detectors, means coupling each respective amplifier input circuit to a respective one of said infinite impedance detectors, and means for combining the detected outputs of said detectors in a predetermined relation.

4. In a frequency modulation receiving system, a pair of regenerative amplifier circuits, each amplifier having a respective signal input tuned circuit, said signal input tuned circuits being oppositely mistuned with respect to a predetermined frequency, means for applying frequency modulated carrier energy to said respective input circuits, the center frequency of the applied energy being equal to said predetermined frequency, a quench oscillator for alternately quenching said amplifiers thereby to render them operative as super-regenerative amplifiers, a pair of infinite impedance detectors, means coupling each respective amplifier input circuit to a respective one of said infinite impedance detectors, means for combining the detected outputs of said detectors in a predetermined relation, and said

combining means including a switch which is adapted to selectively combine said detected outputs in push-pull relation for frequency modulation reception, or in push-push relation for amplitude modulation reception.

5. In a signalling system, at least one oscillator tube circuit, means for applying frequency modulated radio signals thereto, means for quenching the oscillator at a superaudible frequency to provide super-regenerative amplification, a detector of the infinite impedance type coupled to the oscillator for deriving the modulation signals, a second oscillator tube circuit, said two oscillators being oppositely mistuned relative to the mean frequency of the applied radio signals, said quenching means acting on the two oscillator tubes in alternate manner, and a separate infinite impedance detector coupled to the second oscillator and purely capacity-resistance means coupling each detector to its respective oscillator.

6. In a frequency modulation receiving system, a pair of regenerative amplifier circuits, each amplifier having a respective signal input tuned circuit, said signal input tuned circuits being oppositely mistuned with respect to a predetermined frequency, means for applying frequency modulated carrier energy to said respective input circuits, a quench oscillator for alternately quenching said amplifiers thereby to render them operative as super-regenerative amplifiers, a pair of detectors, means coupling each respective amplifier input circuit to a respective one of said detectors, and means for combining the detected outputs of said detectors in push-pull relation.

7. In an amplitude modulation receiving system, a pair of regenerative amplifier circuits, each amplifier having a respective signal input tuned circuit, means for applying modulated carrier energy to said respective input circuits, said amplifier input circuits being oppositely mistuned relative to a reference frequency, a quench oscillator for alternately quenching said amplifiers thereby to render them operative as super-regenerative amplifiers, a pair of infinite impedance detectors, means coupling each respective amplifier input circuit to a respective one of said infinite impedance detectors, means for combining the detected outputs of said detectors, said combining means including a switch which is adapted to selectively combine said detected outputs in push-push relation for amplitude modulation reception.

8. In a receiving system, a pair of regenerative amplifier circuits, each amplifier having a respective signal input tuned circuit, said signal input tuned circuits being oppositely mistuned with respect to a predetermined frequency, means for applying modulated carrier energy to said respective input circuits, the center frequency of the applied energy being equal to said predetermined frequency, a quench oscillator for alternately quenching said amplifiers thereby to render them operative as superregenerative amplifiers, a pair of detectors, means coupling each respective amplifier input circuit to a respective one of said detectors, and means for combining the detected outputs of said detectors in a predetermined relation.

9. In an angle modulated carrier energy receiving system, a pair of regenerative amplifier circuits, each amplifier having a respective signal input tuned circuit, said signal input tuned circuit,

cuits being oppositely mistuned with respect to a predetermined frequency, means for applying modulated carrier energy to said respective input circuits, the center frequency of the applied energy being equal to said predetermined frequency, a quench oscillator for alternately quenching said amplifiers thereby to render them operative as super-regenerative amplifiers, a pair of detectors, means coupling each respective amplifier input circuit to a respective one of said detectors, and combining means including a switch which is adapted to selectively combine said detected outputs in push-pull relation for frequency modulation reception, or in push-push relation for amplitude modulation reception.

10. In a receiving system, a pair of regenerative amplifier circuits, each amplifier having a respective signal input tuned circuit, said signal input tuned circuits being oppositely mistuned with respect to a predetermined frequency, means for applying modulated carrier energy to said respective input circuits, a quench oscillator constructed and arranged for alternately quenching said amplifiers thereby to render them operative as super-regenerative amplifiers, a pair of detectors, quench current blocking means coupling each respective amplifier to a respective one of said detectors, and means for combining the modulation outputs of said detectors in a predetermined relation.

11. In a receiving system, a pair of regenerative amplifier circuits, each amplifier having a respective signal input tuned circuit, means for applying modulated carrier energy to said respective input circuits, a quench oscillator constructed and arranged for alternately quenching said amplifiers thereby to render them operative as super-regenerative amplifiers, a pair of detectors, means coupling each respective amplifier input circuit to a respective one of said detectors, a switch connected to the output circuits of the detectors adapted selectively to combine the detected outputs in push-pull relation for frequency modulation reception, or in push-push relation for amplitude modulation reception.

12. In a signalling system, a pair of oscillator tube circuits, a discriminator network coupled to said oscillator tubes, means for applying frequency modulated radio signals to said discriminator network, means for alternately quenching the oscillator circuits at a superaudible frequency to provide super-regenerative amplification, and a respective detector separately coupled to said discriminator network for deriving the modulation signals.

13. In a receiving system, a pair of regenerative amplifier circuits, each amplifier having a respective signal input circuit, said signal input circuits providing sloping filter characteristics of complementary nature, means for applying modulated carrier energy to said respective input circuits, the center frequency of the applied energy being equal to the cross-over frequency of the characteristics, a quench oscillator for alternately quenching said amplifiers thereby to render them operative as super-regenerative amplifiers, a pair of detectors, means coupling each respective amplifier input circuit to a respective one of said detectors, and means for combining the modulation outputs of said detectors in a predetermined relation.

MURRAY G. CROSBY.
